UNITED STATES PATENT OFFICE.

JOHN EDER, OF PHILADELPHIA, PENNSYLVANIA.

AUTOMATIC EJECTOR FOR BOTTLE-LABELING MACHINES.

Application filed October 1, 1927. Serial No. 223,360.

This invention relates to means for automatically ejecting bottles, especially vials, from a bottle labeling machine after the labels have been applied thereto.

5 In machines of this character the vials are fed to and removed from the machine manually, which necessarily makes the operation slow.

10 The principal object of this invention is to speed up the production of the machine by automatically ejecting the bottles, and thus relieving the operator of one operation. The operator is required merely to feed the vials to the machine.

15 Referring to the drawings:

Fig. 1 is a front elevation of my invention, and illustrates sufficient of a bottle labeling machine to demonstrate the utility of my invention as applied thereto;

20 Figure 1^a is a continuation of Fig. 1;

Fig. 2 is a view similar to Fig. 1, and illustrating the elements of the machine in a subsequent position;

25 Fig. 3 is a side elevation of the mechanism shown in Fig. 2;

Figs. 4, 5, 6 and 7 illustrate the various labeling and ejecting operations, Fig. 5 being a sectional elevation taken on the line 5—5, Fig. 3.

30 Fig. 8 is a perspective view of a detail of the machine.

Fig. 9 is a front elevation of sufficient of a bottle labeling machine of the type to which my invention is especially adapted, to illustrate the mechanism by which the various elements of the machine are operated, the greater part of the frame of the machine having been omitted for the purpose of clarity;

35 Figs. 10, 11 and 12 are sectional elevations taken on the lines 10—10, 11—11 and 12—12, respectively, of Fig. 9, these views being drawn on a reduced scale relative to that of Fig. 9.

40 In machines of the type to which my invention is particularly adaptable, the vials *a* are manually placed on a supporting anvil 1, a label depositing arm 2 then places a label *x*, which previously has had a coating of glue or similar adhesive material applied thereto, on the vial *a* (see Figs. 1 and 4) and immediately an arm 3, having a holding shoe 4 thereon, descends, the shoe engages the label *x* pressing its center tightly against the vial *a*, while the depositing arm 2 moves away

45 A pair of wiper arms 5, 5 having resilient wiping tongues 6, 6 thereon are moved from the position shown in Fig. 1 to that shown in Fig. 2, wherein the tongues 6, 6 engage the opposite ends of the label *x* (see Fig. 5) and as the arms 5, 5 continue their movement the tongues 6, 6 wipe the said label around the vial in the manner illustrated in Figs. 5 and 6.

50 The operator is then required to remove the labeled vial and place an unlabeled one in its place on the anvil 1.

55 My invention relates to means for automatically ejecting the labeled vial from the anvil, and consists of a blade 10 which is rigidly secured at one of its ends to the label holding arm 3.

60 This arm, as is apparent from the drawings, is pivoted at 7 and receives a rocking motion. As this arm moves from its label holding position to various positions, including that shown in broken lines in Fig. 1, the free end of the blade 10 moves toward and then strikes the labeled vial (see Figs. 6 and 7), the impact causing the vial to fall over the longitudinal side edge of the anvil 1 into a receiving hopper 11, which 65 is secured to the rigid portion 9 of the machine on which the anvil 1 is mounted.

70 To facilitate the feeding of the unlabeled vials to the anvil 1, I mount on the rigid portion 9 of the machine a feeding tube 12 which is cut away, as at 13, to facilitate the placing of the vials in the tube.

75 When the ejecting blade 10 removes a labeled vial from the anvil 1, the operator merely places a new vial in the cut-away portion 13 of the tube 12, and by pressing the new vial inwardly advances a previously inserted vial from the rear end of the tube 12 onto the anvil 1 and continues to press the new vial until the vial now advances onto 80 the anvil engages an adjustable stop 14 on the anvil.

85 As shown in the drawings, the anvil 1 comprises a horizontal bar 15 having a V-shaped vial supporting groove or trough 16 formed on its upper face. The bar 15 is provided with legs 17, 17 formed integral therewith, and is provided with feet 18, 18 which rest on the rigid portion 9 of the machine, being secured thereto by means of bolts 19, 19. On 90 one of the legs 17 is integrally formed a bracket 20 in which is provided a screw 21, which forms the adjustable stop 14 above referred to. A locking screw 22 secures the stop screw in its adjusted position. The lon-

itudinal side walls of the bar 15 are cut away between the legs 17, 17, as shown at 23, permitting the ejecting blade 10 to engage the vial.

The ejecting blade 10 is composed of two sections 10^a and 10^b for the purpose of permitting adjustment of the blade. The section 10^a is secured to the label holding arm 3 by means of a bolt 25. Each of the sections 10^a and 10^b is slotted as at 26 for the reception of a securing bolt 27. An aligning element 28 is mounted on the bolt 27 and is provided with side flanges 29, 29 between which the sections 10^a and 10^b are positioned, thus the section 10^b can be adjusted longitudinally on the section 10^a and the whole secured together as a rigid element by means of the bolt 27. The free end of the section 10^b is offset as shown at 30 in order that the blade will engage the vial approximately at the center thereof, and between the legs 17, 17 of the anvil 1.

The receiving hopper 11 has a lip 31 overlying the frame member 9 to which it is secured by screws 32. The hopper is provided with a spout 33 which terminates in a right angle turn formed by an end plate 34 secured thereto. One side of the interior of the hopper 11, one side of the spout 33 and the end plate 34 are each provided with a lining composed of resilient shock-absorbing material 35, such as felt, against which the vials strike when ejected from the anvil 1, thus preventing breakage of the vials. The spout 33 delivers the vials into any suitable form of receptacle 36.

The feeding tube 12 is provided with suitable legs 37, 37 having feet 38, 38 which are secured to the frame member 9 at one end of the tube by means of a screw 40, and at the other end by the screw 19 which secures one of the feet 18 of the anvil 1 to the frame member 9, this foot 38 of the feeding tube being positioned on top of the said anvil foot.

As illustrated in Figs. 9 to 12 inclusive, the label depositing arm 2, the arm 3 which carries the holding shoe 4, and the wiper arms 5, 5 which carry the wiping tongues 6, 6, are operated in timed relation with respect to each other from a common operating shaft 50 which is rotatably mounted in the frame of the machine and is continuously rotated by any suitable power means, not shown.

As shown in Figs. 9 and 10, the label depositing arm 2 is pivotally mounted on a shaft 51 carried by the frame of the machine and has a rearwardly extending arm 52 which is operatively connected by a link 53 to one end of a lever 54, the opposite end of which is pivotally mounted on a shaft 55 carried by the frame of the machine. Intermediate its ends the lever 54 is provided with a roller 56 which bears against a cam 57 secured to the main shaft 50, a spring 58 causing the roller 56 to follow the contour of the

cam 57 and thereby effect operation of the label depositing arm 2 in proper timed relation with respect to the operation of the holding shoe 4 and the wiping tongues 6.

As shown in Figs. 9 and 11, the lever 3, 70 which carries the holding shoe 4, is pivotally mounted on a rod 60, carried by the frame of the machine, and connected by a link 61 to one end of a lever 62, the opposite end of which is pivotally mounted on a rod 63 carried by the frame of the machine. Intermediate its ends the lever 62 is provided with a cam follower 64 which rides in a cam groove 65 formed in a cam 66 secured to the main operating shaft 50. By this means the holding shoe 4 is operated in proper timed relation with respect to the depositing lever 2 and the wiper tongues 6. 80

As shown in Figs. 9 and 12, the wiper tongues 6 are carried by the arms 5, and the arms 5 are pivotally mounted on studs 70 carried by the frame of the machine, a portion of which is illustrated at 71. The arms 5 are connected by links 72 to a bar 73 slidably mounted in the frame portion 71. A link 74 is connected at one of its ends to the slide bar 73 and at its opposite end to one end of a lever 75. The opposite end of the lever 75 is pivotally mounted on the rod 63 above noted. Intermediate its ends the lever 75 is provided with a cam follower 76 which rides in a cam groove 77 formed in a cam 78 secured to the main operating shaft 50. By this means the wiper tongues 6, 6 are operated in proper timed relation with respect to the depositing arm 2 and the holding shoe 4. 105

While I have described my invention as being used in a machine for labeling vials, obviously bottles of larger size and different shapes may be labeled and ejected by the mechanism above described, without departing from the essential features of the invention. 110

I claim:

1. In combination with a bottle labeling machine having a bottle supporting anvil, means for placing a label on the bottle, means for wiping the label around the bottle and means for holding the label during the wiping operation; means, operable by the label holding means, for ejecting the bottle from the anvil. 115

2. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage the labeled bottle and remove it from the anvil as the 120

holding arm moves to its inoperative position after the bottle has been labeled.

3. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage the labeled bottle and remove it from the anvil as the holding arm moves to its inoperative position after the bottle has been labeled; and means for adjusting the blade relative to the anvil.

15 4. In combination with a bottle labeling machine having a bottle supporting anvil, a label depositing arm for placing a label on a bottle supported by the anvil, a pivoted label holding arm, and a pair of label wiping arms; a bottle ejecting blade consisting of a section secured to said label holding arm and a section adjustably secured to the first said section.

25 5. In combination with a bottle labeling machine having a bottle supporting anvil, a label depositing arm for placing a label on a bottle supported by the anvil, a pivoted label holding arm, and a pair of label wiping arms; a bottle ejecting blade consisting of a section secured to said label holding arm and a section adjustably secured to the first said section; means for maintaining alignment between said sections; and means for rigidly securing the sections in their relatively adjusted positions.

30 6. In combination with a bottle labeling machine having a bottle supporting anvil, a label depositing arm for placing a label on a bottle supported by the anvil, a pivoted label holding arm, and a pair of label wiping arms; a bottle feeding tube aligned with said anvil; and an ejecting blade secured to said label holding arm, and adapted to strike the bottle located on the anvil for removing the said bottle from the anvil.

40 7. In combination with a bottle labeling machine having a bottle supporting anvil, a label depositing arm for placing a label on a bottle supported by the anvil, a pivoted label holding arm, and a pair of label wiping arms; a bottle feeding tube aligned with said anvil; a stop on said anvil for positioning the bottle thereon in correct relation to the label depositing arm; and an ejecting blade secured to said label holding arm, and adapted to strike the bottle located on the anvil for removing the said bottle from the anvil.

45 8. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage

the labeled bottle and remove it from the anvil as the holding arm moves to its inoperative position after the bottle has been labeled; and a hopper adapted to receive the ejected bottles.

70 9. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage the labeled bottle and remove it from the anvil as the holding arm moves to its inoperative position after the bottle has been labeled; a hopper adapted to receive the ejected bottles; and a spout on said hopper delivering the ejected bottles into a suitable receiving receptacle.

75 10. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage the labeled bottle and remove it from the anvil as the holding arm moves to its inoperative position after the bottle has been labeled; a hopper adapted to receive the ejected bottles; a spout on said hopper delivering the ejected bottles into a suitable receiving receptacle; and a deflecting plate at the delivery end of said spout.

80 11. In combination with a bottle labeling machine having a bottle supporting anvil, a label depositing arm for placing a label on a bottle supported by the anvil, a pivoted label holding arm, and a pair of label wiping arms; a bottle ejecting blade having one of its ends secured to the pivoted label holding arm and its opposite end adapted to engage the labeled bottle and remove it from the anvil as the holding arm moves to its inoperative position after the bottle has been labeled; a hopper adapted to receive the ejected bottles; a spout on said hopper delivering the ejected bottles into a suitable receiving receptacle; a deflecting plate at the delivery end of said spout; and means for absorbing the shock of impact in the hopper and its associated bottle receiving elements.

85 12. In combination with a bottle labeling machine having a bottle supporting anvil provided with a bottle receiving and supporting groove in its upper face and a stop at one end of said anvil for positioning the bottles thereon; a guiding element aligned with the opposite end of the anvil to facilitate the feeding of the bottles to the said groove.

90 13. In combination with a bottle labeling machine having a bottle supporting anvil provided with a bottle receiving and supporting groove in its upper face; a bottle

feeding tube located at one end of the anvil for guiding the bottles into the groove in the anvil, and having a portion of its upper side removed to facilitate the placing of the bottles in the tube.

14. In combination with a bottle labeling machine having a bottle supporting anvil provided with a bottle receiving and supporting groove in its upper face and means for holding a label against a bottle located on the anvil; a bottle feeding tube located at

one end of the anvil for guiding the bottles into the groove in the anvil, and having a portion of its upper side removed to facilitate the placing of the bottles in the tube; and an ejecting blade carried by said label holding means and adapted to engage the bottle and remove it from the anvil when the label holding means moves away from the bottle.

15 JOHN EDER.
